UNITED STATES PATENT OFFICE.

KENNETH J. UNWIN AND WALTER H. WAKEFIELD, OF WORCESTER, MASSACHUSETTS,
ASSIGNORS TO CROMPTON & KNOWLES LOOM WORKS, OF WORCESTER, MASSACHUSETTS, A CORPORATION OF MASSACHUSETTS.

TUBE FRAME FOR AXMINSTER LOOMS.

Application filed November 8, 1926. Serial No. 146,938.

This invention relates to tube frames for Axminster looms and it is the principal object of the invention to improve upon the construction heretofore in use to the end that the strains to which the supporting elements of the tube frame are subjected shall be reduced.

The usual Axminster loom comprises a pair of spaced endless intermittently moving chains between which extend a complement of tube frames. The tube frames are attached to the chain by means of hooks and tongues, the tongue passing between the members of a double link and the hook extending over one of the members. As heretofore constructed the chain has been located at a point not only above the tube frame bar but also above the axis of the spools, and the result of this construction is to place the entire weight of the tube frame to one side of the supporting tongues and hooks. As the chain is transported it passes over and under guide sprockets and it is found that as the frame passes from one side to the other of an upper sprocket the tube frame moves by gravity to assume a new position and the strain of this movement is borne by the hook and chain.

It is an important object of our present invention to locate the chain at a point intermediate the axis of the spools and the axis of the carrier bar of the tube frame so that the spools will have a counterbalancing effect on the carrier bar and thus reduce the strain to which the hook is subjected.

It is a further object of our invention to provide a rigid latch pivoted to the bracket of the ordinary tube frame and located to have direct contact with the clutch of the Axminster loom.

It is a still further object of the invention to provide for rocking the tube frames about the axis of the clutch by means so constructed as to permit the location of the transporting chain in a position lower than has been possible under previous constructions.

A more specific object of our invention is to provide a tube frame bracket having an upper bearing for the rigid hook and having the lower part thereof formed with parallel arms to enter a tubular bar, said bracket having spool bearing and chain engaging

parts secured together and each having one of the arms formed therewith.

With these and other objects in view which will appear as the description proceeds, our invention resides in the combination and arrangement of parts hereinafter described and set forth in the claims.

In the accompanying drawings wherein we have shown a convenient embodiment of our invention,

Fig. 1 is a front elevation of a tube frame made according to our invention and showing the relation the same sustains to the chain, sprocket, and clutch of an Axminster loom, these latter parts being shown in section,

Fig. 2 is an end elevation taken in the direction of arrow 2, Fig. 1,

Fig. 3 is an enlarged front elevation, parts being in section, showing the parts in substantially the position in which they are shown in Fig. 1,

Fig. 4 is a view similar to Fig. 3 but with the parts moved to releasing position,

Fig. 5 is an end elevation looking in the direction of arrow 5, Fig. 3, the chain and clutch being omitted,

Fig. 6 is a horizontal section on line 6—6 of Fig. 4,

Fig. 7 is a detail top plan view taken in the direction of arrow 7, Fig. 5, and showing the top of the tube frame bracket, and

Fig. 8 is a detail perspective view of a portion of one of the brackets by which the tube frame is held to the chain.

Referring to Figs. 1 and 2 the usual pull-over shaft which extends across the Axminster loom is indicated at 10 and has keyed thereto at each end thereof a sprocket 11, only one sprocket being shown. A clutch arm 12, one located at each side of the loom, has a stud 13 to which is secured a clutch 14. By means not shown the arm 12 (shown in Fig. 2) together with the one on the opposite side of the loom is lowered and raised each time a row of tufts is to be inserted in the fabric. Each sprocket 11 is provided with a chain 15 having double links 16 and intervening single links 17 and by means of mechanism not shown but well understood the pullover shaft 10 and hence the chain are given intermittent motions so as to present a new double link and parts associated

therewith to operative position each time a new row of tufts is to be woven into the fabric.

The tube frame designated generally 5 at 18 comprises a lower horizontal preferably metallic and tubular carrier bar 19 to which are secured a large number of small yarn receiving tubes 20 and there are provided the requisite number of spools for 10 the yarn, one spool being indicated at 21 in the drawings. Said spools have the yarn wound thereon in the order called for by the pattern and the yarns pass through the tubes 20 and extend below the tubes in order 15 to form the tuft. The matter thus far described may be of common construction except for the location of the chains 15 relatively to the axis of the spools 21, as will be set forth more fully hereinafter.

20 The spool 21 is held in fixed position relatively to the bar 19 by an upwardly extending bracket member 30 provided with a spool bearing 31 for the gudgeon of the spool, said member 30 having a horizontal arm 32 which 25 lies adjacent and is secured in any approved manner to the top wall of the carrier bar 19.

A second bracket member 33 has an offset tongue 34 which passes between the members of the double link 16 to hold the tube frame 30 in proper longitudinal position. The member 33 has a vertical part 35 extending along a part of member 30 and has the lower end formed as an arm 36 extending into and secured in any approved manner 35 to the bottom of the tubular bar. In order that the two members may be secured together we have stamped out a pair of spaced fingers 37 from a portion of the horizontal arm 32 of the member 30 and extend the 40 same vertically to lie adjacent the portion 35 of the chain engaging member and weld these two parts together.

The tube frame is supported on the chains by means of hooks one of which is indicated in the drawings at 40. Member 30 is extended above the bearing 31 for the spools and provided with parallel spaced wings 41 as shown in Figs. 5 and 7, and a pin 42 is secured to these wings and passes through 50 curved end 43 of the hook to afford a pivotal connection for the latter.

The hook extends downwardly from the pin 42 and has struck from the sides thereof ears 44 which are positioned to lie over one 55 of the members of the double link 16. The lower end 45 of the hook lies below the ears 44 and extends through and is guided by a slot 46 in member 33. The hook is held yieldingly against the member 33 at the 60 right hand end of the slot 46 by means of a compression spring 47 interposed between member 30 and hook 40 and held in position by a small projection stamped out of hook 40. The clutch 14 has a recess 48 which receives the lower end 45 of the hook 40.

As shown in Figs. 1 and 2 the stud 13 extends through and projects beyond the arm 12 to have secured thereto an arm 50 the upper end of which is attached to a rocking rod 51 by a stud 52. Stud 13 is free to rock in the arm 12 to cause oscillation of the clutch 14, but we do not wish to be limited to the particular structure shown for rocking said clutch.

Under normal conditions the chain will be given an intermittent movement and as a tube frame moves to the position shown in Fig. 2 under the pullover shaft 10 the arms 12 will first be moved toward the tube frame in a direction substantially parallel to the axis of said frame. The rounded upper surface of lip 49 will engage the bottom of the tube frame to lift the same, thus taking the strain of supporting the tube frame off the ears 44. As the clutch continues to move toward the tube frame the lower end 45 of the hook will enter the recess 48 and will thereafter be engaged by a part of the clutch and move from the position shown in Fig. 3 to that shown in Fig. 4, where it will be seen that the ears 44 are moved clear of the left hand member of the double link 16 and the clutch is in direct contact with the portion 35 of the bracket. The arms 12 will thereafter be given a downward movement so that tongues 34 will move out of the double links and the yarn tubes 20 will be inserted through the warps. While in this position rod 51 will be moved longitudinally to rock the stud 13 by devices not shown but designated at 1 in U. S. Patent No. 186,374 to Smith et al. The rocking of the clutch produces a corresponding rocking on the part of the tube frame for the purpose of inserting the tuft yarns in the fabric. The rod 51 is then restored to normal position, after which the arms 12 are raised and then moved away from the tube frames, the reverse operations to those already described taking place so that the parts pass from the position shown in Fig. 4 to that shown in Fig. 3 with the tube frame entirely supported on the chain.

As previously set forth it is an important object of our invention to dispose the tube frame and spool on opposite sides of the supporting chain to the end that all the weight does not lie on one side when the tube frames move with the chains about the sprockets of the chain supporting structure. By the structure set forth herein the spools counterbalance in part the weight of the tube frame with the result that the hooks 40 are subjected to less strain than has been the case heretofore.

From the foregoing it will be seen that we have provided a construction wherein the transporting chain lies intermediate the axis of the spools and the carrier bar and that the clutch has direct contact with the portion 35 of the member 33 because of the fact that

the recess 48 receives the lower end 45 of the hook. It will further be seen that the slot 46 is of such length as to limit outward movement of the hook 40 under action of the spring 47 and thus correctly position the ears 44 relatively to the tongue 34. Also, the two members of the bracket have vertical portions secured together as shown in Fig. 8 while at the same time permitting the tongue 34 and upper part of member 30 to be of sufficient width.

Having thus described our invention it will be apparent that changes and modifications may be made therein by those skilled in the art without departing from the spirit and scope of the invention, and we do not wish to be limited to the details herein disclosed, but what we claim is:

1. In an Axminster loom, a transporting chain, a tube frame comprising a longitudinal bar having yarn tubes secured thereto, a spool mounted on the tube frame and having the axis thereof spaced from the axis of the bar, and means for detachably connecting the tube frame to the chain, said means and chain having contact with each other at a point between the axis of the bar and the axis of the spool, whereby a part of the weight to be supported by said means lies on each side of the point where the same engages the chain.

2. In an Axminster loom, a tube frame comprising a longitudinal bar having a plurality of yarn tubes secured thereto, a spool mounted on the tube frame and having the axis thereof removed from the axis of the bar, a movable supporting member for the tube frame, and a transporting chain engaging said member and located at a point intermediate the axes of the bar and spool, whereby a part of the weight of the tube frame and spool will lie on each side of the chain.

3. In an Axminster loom, a tube frame comprising a longitudinal bar having a plurality of yarn tubes secured thereto, a yarn spool having the axes thereof spaced from the axis of the bar, a bracket to connect the bar and spool together and hold the same in spaced relation, a supporting chain located between the axis of the bar and the axis of the spool, and detachable connections between the bracket and chain to support said tube frame, spool, and bracket, the weight of the spool lying on one side of the chain and the weight of the carrier bar lying on the other side of the chain.

4. In an Axminster loom, a tube frame comprising a longitudinal bar having a plurality of yarn tubes secured thereto, a yarn spool having the axis thereof spaced from the axis of the bar, a bracket connecting the bar and spool and holding the same in spaced relation, a supporting chain located between the axis of the bar and the axis of the

spool, and a movable rigid latch member pivoted on the bracket at a point above the axis of the spool and extending downwardly to have holding contact with the chain.

5. In an Axminster loom having a supporting chain, a tube frame comprising a bar having a plurality of yarn tubes secured thereto, a yarn spool, a bracket secured to the tube frame and supporting the spool, a clutch movable in a direction parallel to the axis of the bar into engagement with the tube frame, a depending rigid spring stressed latch pivoted to the bracket at a point above the axis of the spool and extending downwardly to have supporting engagement with the chain and having a portion to be engaged directly by said clutch as the same moves toward the tube frame.

6. In an Axminster loom, a tube frame comprising a bar having a plurality of yarn tubes secured thereto, a yarn spool having the axis thereof spaced from the axis of the bar, a bracket secured to the bar and supporting the spool, a rigid latch member pivoted to the bracket at a point above the axis of the spool, a supporting chain located between the axis of the bar and the axis of the spool, and a clutch movable toward the tube frame, said latch being yieldingly held in holding engagement with the chain at a point intermediate the axis of the bar and the spool and having direct engagement with the clutch as the latter moves toward the bar to be released from the supporting chain.

7. In a tube frame for Axminster looms, a hollow tubular bar provided with a plurality of yarn tubes, a yarn spool, a bracket for said bar comprising two members, one of said members having a horizontal portion to extend into the bar and having also an upwardly extending portion to support the spool, said member having also a downwardly extending portion to project below the horizontal portion, the other member having a horizontal portion projecting into and secured to the bar and having a vertical portion secured to the depending part of the first named member, said second named member also having a portion thereof offset to engage a supporting chain, and a rigid latch pivoted to the first named member and engaging the chain.

8. In a tube frame for Axminster looms having a supporting chain, a hollow tubular bar provided with a plurality of yarn tubes, a yarn spool, a bracket for connecting the bar and spool formed of two members both of which have vertical portions extending in a direction transverse to the axis of the bar and both of which extend into and are secured to the hollow bar, one of said members extending upwardly to support the spool and having a finger struck from the intermediate portion thereof and extending downwardly to lie parallel to and adjacent a part of the

other member and being secured thereto, said other member having an offset chain engaging tongue, and movable means carried by one of said members to engage the chain to support the tube frame and spool.

9. In a tube frame for Axminster looms having a supporting chain, a hollow tubular bar provided with a plurality of yarn tubes, a yarn spool, a bracket for connecting the bar and spool formed of two members both of which have vertical portions extending in a direction transverse to the axis of the bar and both of which extend into and are secured to the hollow bar, one of said members extending upwardly to support the spool and having a finger struck from the intermediate portion thereof and extending downwardly to lie parallel to and adjacent a part of the other member and being secured thereto, said 20 other member having an offset chain engaging tongue, and movable means carried by one of said members to engage the chain to support the tube frame and spool, said last named means including a rigid latch pivoted 25 to the first named member and extending downwardly to have engagement with the chain.

10. In a tube frame for Axminster looms having a supporting chain, a hollow tubular bar provided with a plurality of yarn tubes, a yarn spool, a bracket for connecting the bar and spool formed of two members both of which have vertical portions extending in a direction transverse to the axis of the bar and both of which extend into and are secured to the hollow bar, one of said members extending upwardly to support the spool and having a finger struck from the intermediate portion thereof and extending downwardly to lie parallel to and adjacent a part of the other member and being secured thereto, said other member having an offset chain engaging tongue, and movable means carried by one of said members to engage the chain to support the tube frame and spool, said means including a rigid spring pressed member extending downwardly and having ears struck therefrom and projecting outwardly to have engagement with the supporting chain.

In testimony whereof we have hereunto affixed our signatures.

KENNETH J. UNWIN.
WALTER H. WAKEFIELD.
